UNITED STATES PATENT OFFICE.

CALEB K. COLBY, OF NEW YORK, N. Y.

DESIGN FOR WATCH-CASE.

Specification forming part of Design No. 6,201, dated October 15, 1872.

To all whom it may concern:

Be it known that I, CALEB K. COLBY, of the city, county, and State of New York, have invented a new and original Design for a Watch-Case, of which the following is a specification:

The drawing represents a central section of my new form of watch-case.

This invention relates to a new design for the edge of the case proper and for the outer side of the lid or lids of a watch-case.

The case proper A is made with a V-edge, as shown. Each of the lids B B has a sort of bead, a, near the circumference; next to that

an inclined edge, b, whence a step, c, extends down to the convex or other shaped central surface d of the lid. This gives quite a novel and pleasing effect.

The design applies to hunting-cases as well as to open-face watches.

I claim as my invention—

The design for the watch-case A, having the V-edge, as shown.

CALEB K. COLBY.
